UNITED STATES PATENT OFFICE.

EDWIN BECKER AND ERNEST ABER, OF RACINE, WISCONSIN.

ADJUSTABLE METAL-TICKET CHANGER.

Application filed August 20, 1921. Serial No. 494,008.

To all whom it may concern:

Be it known that we, EDWIN BECKER and ERNEST ABER, citizens of the United States, and residents of Racine, in the county of Racine and State of Wisconsin, have invented new and useful Improvements in Adjustable Metal-Ticket Changers, of which the following is a description, reference being had to the accompanying drawings, which are a part of this specification.

This invention relates to metal ticket changers and more particularly to an adjustable type of metal ticket changer.

It is one of the objects of the invention to provide a metal ticket changer suitable for use by street car operators and especially adapted for use on the "one man car."

A further object of the invention is to provide a metal ticket changer which will readily discharge the metal tickets.

A further object of the invention is to provide a metal ticket changer which can be adjusted to discharge any number of metal tickets at once.

25 A further object of the invention is to provide an adjustable metal ticket changer which is of simple construction, is strong and durable and inexpensive to manufacture, and is well adapted for the purposes described.

30 With the above and other objects in view, the invention consists of the improved adjustable metal ticket changer and its parts and combinations as set forth in the claims, and all equivalents thereof.

In the accompanying drawing in which the same reference numerals indicate the same parts in all of the views:

Fig. 1 is a side view of the adjustable metal ticket changer;

Fig. 2 is a vertical sectional view taken on line 2—2 of Fig. 1; and

Fig. 3 is a horizontal sectional view taken on line 3—3 of Fig. 1.

45 Referring now more particularly to the drawing, the numeral 5 represents a cylindrical barrel of sufficient diameter to receive the metal tickets and of sufficient height to allow it to contain preferably sixty of said metal tickets. The outer surface 6 is provided with a plurality of spaced apertures 7 for the purpose of showing the number of metal tickets in said barrel 5 at any time. The top of the barrel is provided with a removable flanged cap 8 to prevent the tickets from falling out of said barrel.

A plate member 9 is adjustably connected to said barrel 5 by bolts 10 and elongated slots 11. The plate member 9 has formed at right angles to it and as a continuation thereof a base 12 having an off-center aperture 13 of sufficient diameter to allow the free removal therethrough of the metal tickets. Pivottally connected to said base 12, as at 18, normally alined with barrel 5 and positioned between the lower extremity of said barrel and the base plate 12 is a hollow cylindrical device 14 consisting of two telescopically fitted members. A coiled spring 15 surrounds the outer member, and its upper end bears against the shoulder 16 at the upper end of the inner member, and its lower end bears against the flanged base of the outer member. Thus, by means of said slot and bolt connections 10 and 11 the barrel 5 may be raised or lowered and in so doing, coiled spring 15 is expanded or compressed thereby increasing or decreasing the height of the telescoping member 14. In this manner, the number of tickets to be discharged at one time can be regulated. As is best shown in Fig. 3, the normal position of the telescoping member 14 is such that its discharge extremity does not coincide with the off-center aperture 13 of base member 12. By this means, the metal tickets are normally held securely in barrel member 5 and telescoping member 14.

As has heretofore been explained the number of tickets to be discharged at one time can be regulated and in so doing, the height of telescoping member 14 is varied. Therefore, the tickets ready for discharge will always be disposed in said telescoping member. As fully set forth above, said telescoping member is pivotally mounted on the base 12 and this pivotal connection 18 affords the means for discharging the tickets. Telescoping member 14 can be swung in a clockwise direction until it meets stop post 17 when the off-center aperture 13 will coincide with the discharge extremity of telescoping member 14 allowing the tickets contained in member 14 to drop into the hand of the operator. For conveniently moving telescoping member 14, a thumb plate 19 is provided. A coiled spring 20 connected to plate 9, as at 21, and to the telescoping member 14 near the thumb plate 19 affords means for automatically returning said telescoping member to its normal position after it has been moved to discharge tickets.

A lock lug 22 is pivotally connected to base 12 as at 23, and when swung as shown in Fig. 3, it locks the telescoping member 14 in normal position thus preventing any unauthorized movement of said telescoping member and the accidental discharge of tickets carried therein. Lock lug 22 is further adapted to be pivoted in a counter clockwise direction until it is positioned so that plate 19 will clear it and then, the metal ticket changer may be freely operated.

From the foregoing description it will be seen that the improved adjustable metal ticket changer is of very simple construction, and is well adapted for the purposes described.

What we claim as our invention is:

1. A metal ticket changer comprising tubular ticket holding means, registering aper-

ture ticket discharging means, and a telescoping member for regulating the number of tickets to be discharged through the registering apertures.

2. A metal ticket changer comprising a frame member, tubular ticket holding means longitudinally adjustably secured to said frame member, ticket discharging means on said frame member, and means for adjustably regulating the number of tickets to be discharged, said means comprising two telescopically fitted members automatically adjustable by the longitudinal adjustability of said tubular ticket holding means and by coiled spring means.

In testimony whereof we affix our signatures.

EDWIN BECKER.
ERNEST ABER.
